UNITED STATES PATENT OFFICE.

GEORGE HERBERT CONDICT AND VICTOR ANGERER, OF PHILADELPHIA, PENNSYLVANIA, ASSIGNORS TO THE ELECTRIC CAR COMPANY OF AMERICA, OF SAME PLACE.

ELECTRIC CAR.

SPECIFICATION forming part of Letters Patent No. 400,830, dated April 2, 1889.

Application filed June 20, 1888. Serial No. 277,670. (No model.)

To all whom it may concern:

Be it known that we, GEORGE HERBERT CONDICT and VICTOR ANGERER, both of the city and county of Philadelphia, and State of Pennsylvania, have invented an Improvement in Electric Railways, of which the following is a specification.

Our invention has reference to regulators especially adapted to electric cars; and it consists of certain improvements, all of which are fully set forth in the following specification, and shown in the accompanying drawings, which form a part thereof.

In the operation of cars by electricity it has been customary to arrange upon one or both ends of the car a regulator, so that the current flowing to the motor or motors may be regulated and the car controlled from either end, and whereby it may be run and controlled in either direction. These regulators or switches are more or less expensive, and it is desirable to make one suffice to each car.

Our present invention comprehends such a regulator arranged upon the under part of the car, or elsewhere, with connecting mechanism extending to each end or platform of the car, and detachably supported at either end of the car is an operating lever or handle which when shifted from one end to the other in reversing the travel of the car is automatically connected with the connecting mechanism for operating the regulator. By this means the same handle may be shifted to either end, leaving the rear platform of the car free and unobstructed, and used to operate the regulator from the end which is to be the front for the direction of travel of the car. In this way the rear or passenger platform becomes unobstructed, and there is nothing within reach which might accidentally be shifted to interfere with the proper operation of the regulator from the other end. The handle or lever for operating the regulator in producing a given movement of the said regulator is moved in opposite directions at each end to suit the changed position of the operator, and so that pulling the lever toward the operator at either end will perform the same work, and vice versa.

Another feature of the improvement is the employment of a spring which acts directly or indirectly upon the regulator to make it reduce or cut out the current passing to the motor or motors, and which, when operating in conjunction with a suitable locking device for the operating lever or handle—such as a lever detent and rack—prevents the switch accidentally standing at intermediate positions where the resistance would be reduced and danger of burning out exists. 50 55 60

Aside from these features, a spring or snap lock may be employed to insure the regulator moving precisely from one position to the next, and so that it will not stop out of proper position for any particular coupling up of circuits or changes of resistance, and thereby compensate for any loose play in the connections with the operating-lever. 65

It is evident that this improvement may be used for controlling motors which are not on cars or movable vehicles, and that the details may be modified in numerous ways without departing from our invention. 70

The construction of regulator we prefer is what is known as a "barrel-switch," in which a cylindrical contact maker or breaker is rotated on a longitudinal axis, such as set out in G. Herbert Condict's application, Serial No. 271,882, of April 26, 1888; but it is evident that the regulator may be made in a variety 75 80 85 of ways, according as to its duty.

In the drawings, Figure 1 is a plan view of a car-body with our improvements attached thereto. Fig. 2 is a longitudinal sectional elevation of same on line *y y*. Fig. 3 is an end elevation of the regulator and with a portion of the cap broken away. Fig. 4 is a side elevation of the regulator with portions broken away. Fig. 5 is a cross-section of Fig. 2 on line *x x*, and Fig. 6 is a perspective view of 90 one of the socket-plates.

A represents the car-body, and *B B* are its two end platforms.

C C represent two electric motors adapted to propel the said car, and may be connected to the axles in any suitable manner, as is well known in this art. 95

D is a regulator or switch for controlling

the speed and power of the motors, and, as shown, controls the amount of current passing from the battery E, which may be of the secondary type. The current is fed from the 5 battery to the regulator by wires e and from the regulator to the motors by the circuits c.

The regulator D is preferably secured to the under part of the car-body, as shown in Fig. 2, and may have a door, D', whereby its interior may be exposed for examination and repair. The barrel of this regulator or switch is provided on its ends with pinions d, contained within dust-caps G. Working in connection with these pinions are racks II, one of which 15 is arranged below one pinion and the other of which is arranged upon the other pinion, so that pulling either one of the racks toward its respective platform will cause the barrel of the regulator to revolve in the same direction, for reasons hereinafter explained. The 20 racks II have indentations or notches h, into which a pin, I, is pressed by means of a spring, i. There are as many notches h as there are different positions of the barrel for coupling 25 up the motors in different ways—that is to say, in series or parallel or combinations of these. The function of the pin I is to insure the barrel being stopped at the right position. These racks II are connected with slides K 30 under their respective platforms by means of rods J, and these slides K are guided upon guide-rods L, so as to move longitudinally on the car. A spring, M, acts upon one of the rods J and presses upon a stop, m, so as normally to return the barrel of the regulator to 35 its "off" position, or that in which no current is flowing.

Arranged immediately above the slides K are socket-plates F in the platforms B B, 40 which socket-plates have two sockets, f, for receiving the frame-work of the operating-lever.

P is the lever-frame, and has two feet, P', at the bottom and the rack p at the top, and 45 pivoted to this frame is the operating-lever O, having the detent o, and with its lower end extended through the socket-plate F and into a suitable hole, k, in the slide K. The frame P and the operating-lever are removable from 50 the socket-plate on one platform and adapted to be inserted in the socket-plate on the other platform, so as to enable the car to be operated from either end and to enable the entire removal of all obstruction from the rear or 55 passenger platform.

It is evident that by operating the lever O in the same direction with respect to the movement of the car at either end thereof the exact same regulation will take place, and if 60 from any cause the detent o is not brought home in its notch the spring M will instantly return the regulator to its next position in the direction toward cutting off the current. In this way it is impossible for the switch device to stand between two different connections, and thus cause trouble by short-circuiting the battery or other source of current.

It is to be understood that I do not limit myself to any particular detail of construction of the regulator or its connections, nor to the parts 7c P and O, as they may be modified and varied without departing from the principles of the invention. The lever O and its detent and rack mechanism should be such that each notch of the rack p corresponds to a different 75 position of the switch-barrel of the regulator to supply a different current to the motors, and the ratchet-teeth p are made so that the detent may snap back and catch on the tooth next in front. 80

Of course it will be understood that the particular source of electric current is immaterial, as it may be overhead, underground, or surface conductors in place of the secondary or primary battery shown, all of these means 85 of electric supply being well known.

Having now described our invention, what we claim as new, and desire to secure by Letters Patent, is—

1. The combination of a car having a platform, an electric motor to propel the car, a current-regulator to control the current passing to the motor arranged under the body of the car, a positive mechanical device for operating said regulator and extending to the platform, and an operating-lever and fulcrum detachably supported by said platform and having a positive detachable connection with the regulator-operating device, whereby the operating-lever may be readily removed without disturbing the other parts. 90

2. The combination of a car having a platform, an electric motor to propel the car, a current-regulator to control the current passing to the motor arranged under the body of the car, a positive mechanical device for operating said regulator and extending to the platform, an operating-lever detachably supported by said platform having a positive detachable connection with the regulator-operating device, whereby the operating-lever may be readily removed without disturbing the other parts, and a spring independent of the lever to normally move the regulator to reduce or cut off the current. 105

3. The combination of a car having a platform, an electric motor to propel the car, a current-regulator to control the current passing to the motor arranged under the body of the car, a positive mechanical device for operating said regulator and extending to the platform, an operating-lever rack and detent detachably supported by said platform having a positive detachable connection with the regulator-operating device, whereby the operating-lever may be readily removed without disturbing the other parts, and a spring independent of the lever to normally move the regulator to reduce or cut off the current. 115

4. The combination of a car, an electric motor to propel said car, a rotary current-regulator under the car having a transverse axis, and a sliding mechanical mechanism extending to the front of the car and connecting 120

with said regulator by a rack and pinion to rotate it.

5. The combination of a car, an electric motor to propel said car, a rotary-barrel current-regulator under the car, a mechanical mechanism extending to the front of the car to rotate said regulator, and a spring to oppose the rotation of the barrel in one direction and rotate the barrel in the opposite direction to reduce or shut off the current.

6. The combination of a car, an electric motor to propel said car, a rotary-barrel current-regulator under the car, a mechanical mechanism extending to the front of the car to rotate said regulator, a spring to oppose the rotation of the barrel in one direction and rotate the barrel in the opposite direction to reduce or shut off the current, and a locking device to lock the barrel in two or more positions of rotation.

7. The combination, in an electrically-propelled car, of a regulator for the current flowing to the motor, a detachable hand-lever mechanism detachably supported upon the car-platform to move it in one direction, and a spring to move it in the opposite direction to reduce or cut off the current.

8. The combination of a regulator for the current flowing over an electric circuit, a detachable hand-lever mechanism to move it in one direction, a connection between the hand-lever and regulator, a spring acting on the connection and independent of the lever to move it in the opposite direction to operate the regulator to reduce or cut off the current, and a locking device to lock the lever of the regulator in two or more positions to vary the current passing to the circuit.

9. The combination of a car having a platform, an electric motor to propel the car, a current-regulator to control the current passing to the motor arranged under the body of the car, a positive mechanical device for operating said regulator and extending to the platform, an operating-lever detachably supported by said platform having a positive detachable connection with the regulator-operating device, whereby the operating-lever may be readily removed without disturbing the other parts, and a snap-lock between the movable part of the regulator and the frame supporting it to insure the movable part stopping positively at fixed places.

10. The combination of a car, an electric motor to propel said car, a rotary-barrel current-regulator under the car, a mechanical mechanism extending to the front of the car to rotate said regulator, a series of depressions in the regulator-barrel-operating mechanism, and a spring-lock to snap into said depressions to hold the barrel in given positions.

11. The combination of a car, an electric motor to propel said car, a rotary-barrel current-regulator under the car, a mechanical

mechanism extending to the front of the car to rotate said regulator, a spring to oppose the rotation of the barrel in one direction and rotate the barrel in the opposite direction to reduce or shut off the current, a locking device to lock the barrel in two or more positions of rotation, a series of depressions in the regulator-barrel-operating mechanism, and a spring-lock to snap into said depressions to hold the barrel in given positions.

12. The combination of a barrel regulator or switch, a spur-wheel secured to the rotating barrel, a sliding rack meshing with said spur-wheel and moving transversely to the barrel, and a lever to move said rack.

13. The combination of a barrel regulator or switch, a spur-wheel secured to the rotating barrel, a sliding rack meshing with said spur-wheel and moving transversely to the barrel, a lever to move said rack, and a locking device to hold said rack and barrel in two or more positions.

14. The combination of a car having a platform at each end, an electric motor to propel the car, a regulator located under the car, a positive mechanical mechanism to operate the regulator extending to and below each platform of the car, and a detachable operating-handle movable to or from each platform extending from above to below the platform and detachably but positively connectible with the mechanism for operating the regulator at either end of the car.

15. The combination of a car having a platform at each end, a current-regulator for the motor arranged on the car, a rod extending from said regulator to each end of the car to a point below the platforms, an operating-lever-frame support arranged upon each platform, a lever-support detachably connectible to either platform, and an operating-lever carried by the frame and detachably connected with the rod over which it is placed.

16. The combination of a car having a platform at each end, a current-regulator for the motor arranged on the car, a rod extending from said regulator to each end of the car to a point below the platforms, an operating-lever-frame support arranged upon each platform, a lever-support for detachable connection to either platform, an operating-lever carried by the frame and detachably connected with the rod over which it is placed, and a spring acting upon said regulator to cause it to move in opposition to one movement of the lever to move the regulator to reduce or cut off the current to the motor.

In testimony of which invention we hereunto set our hands.

G. HERBERT CONDICT,
VICTOR ANGERER.
